(57) **CLAIM**

The ornamental design for a latch backing plate, as shown and described.

DESCRIPTION

FIG. 1 is a first perspective view of a first embodiment of a latch backing plate;

FIG. 2 is a top view of the latch backing plate of FIG. 1; FIG. 3 is a front side view of the latch backing plate of FIG. 1;

FIG. 4 is a rear side view of the latch backing plate of FIG. 1;

FIG. 5 is a bottom view of the latch backing plate of FIG. 1;

FIG. 6 is a second perspective view of the latch backing plate of FIG. 1;

FIG. 7 is a first side view of the latch backing plate of FIG. 1;

FIG. 8 is a second side view of the latch backing plate of FIG. 1;

FIG. 9 is a first perspective view of a second embodiment of a latch backing plate;

FIG. 10 is a top view of the latch backing plate of FIG. 9; FIG. 11 is a front side view of the latch backing plate of FIG. 9;

FIG. 12 is a rear side view of the latch backing plate of FIG. 9;

FIG. 13 is a bottom view of the latch backing plate of FIG. 9;

FIG. 14 is a second perspective view of the latch backing plate of FIG. 9;

FIG. 15 is a first side view of the latch backing plate of FIG. 9; and,

FIG. 16 is a second side view of the latch backing plate of FIG. 9.

Any components in the appended drawings shown in broken lines are for illustrative purposes only and form no part of the claimed design.

1 Claim, 14 Drawing Sheets
